UNITED STATES PATENT OFFICE.

JOHN McMYLER, OF CLEVELAND, OHIO.

APRON FOR CAR-DUMPING MACHINES.

No. 820,434.

Specification of Letters Patent.

Patented May 15, 1906.

Application filed September 29, 1904. Serial No. 226,445.

To all whom it may concern:

Be it known that I, JOHN McMYLER, a citizen of the United States, residing at Cleveland, in the county of Cuyahoga and State of Ohio, have invented a certain new and useful Improvement in Aprons for Car-Dumping Machines, of which the following is a full, clear, and exact description, reference being had to the accompanying drawings.

This invention is for use in connection with machines which lift a loaded car and turn it over, thereby dumping its contents onto an inclined chute or apron. Such machines are commonly used for dumping cars loaded with coal, and one function of the apron is to convey the coal dumped onto it to a discharge-spout, through which said coal is carried into the holds of vessels.

The coal is liable to be broken during transit or while being dumped, and it is the object of this invention to screen out the slack and small pieces while the coal is sliding down the apron.

The invention may be summarized as the combination, with the inclined apron, of a car-dumping machine, or substantially such an adjustable screen as is shown in the drawings, and hereinafter described and claimed.

In the drawings, Figure 1 is a plan view of an apron to which my invention is applied. The drawings, however, show the screens applied only to the three left-hand sections of said apron. Fig. 2 is a side elevation, the upper part of the apron being shown in section. Fig. 3 is a plan view of a portion of the apron, showing the right-hand screen-section. Fig. 4 is a plan view of one of the adjustable sections, and Fig. 5 is a sectional view taken in the plane of the line 5 5 of Fig. 3.

Referring to the parts by letters, A represents an inclined apron, which is generally of the form commonly employed with car-dumping machines. At its wide upper end it is pivoted on a horizontal pivot *b* to a girder *B* in the usual way. The floor of this apron below the screens is indicated by *a* in Fig. 2, and this floor rests upon a plurality of longitudinal beams *a'*, which, together with suitable transverse beams, constitute what may be called the "frame" of the apron. This floor, however, is absent from the upper part of the apron, and its place is supplied by the screening device. This device includes a plurality of cylindrical bars *C*, which may be hollow. The upper ends of these bars are passed through holes in an upwardly-extend-

ing flange *a*, attached to the apron. The lower ends of these bars are flattened and are secured upon the floor *a* by means of rivets or bolts *a*. Below these bars and in the divisions between the longitudinal beams *a'* are frames *D*, and on the tops of these frames are secured cylindrical bars *E*, which when the frames are in place lie directly below the spaces between the bars *C*. These frames at 65 their upper ends are connected, by means of links *F*, with the upper transverse beams *a* of the apron and are thereby prevented from moving toward the lower front end of the apron and also from moving transversely. 70 There are as many of these frames and their bars *E* as there are sections between longitudinal beams *a'*.

Two shafts *G* extend transversely of the apron and beneath all of these frames and 75 are mounted in suitable bearings. To these bars numerous cams *g g'* are secured, and these cams engage with the bars *H*, which are secured to the frames *D*, but are adjustable thereon, said bars, however, being rigid parts 80 of said frame when the described mechanism is ready for use. Referring specifically to the manner of connecting these bars with said frames, it will appear from the drawings that each bar is pivoted to the frame and 85 that its free end engages with a bolt *h*, which passes through it and a part of the frame and has an adjustable nut *h'* just above and in contact with the bar *H*. On the right-hand end of each of the shafts *g g'* are bevel-gears 90 *g* *g'*, respectively, which engage with bevel-gears *j j'*, secured to a shaft *J*, and this shaft is provided with a hand-wheel or some other convenient means for turning it. It is obvious that by turning this shaft *J* both of the 95 shafts *G* will be turned, whereby their cams will raise the frames *B* more or less or permit them to drop more or less, and thereby vary the width of the spaces between the bars *C* and *E*, through which the screened material 100 must pass. The bars *H* are made adjustable, because there will be many of the frames *D*, and it will require exceedingly nice work to construct them in the shop so that when put onto the machine the bars *E*, which they 105 carry, will all be precisely at the same distance from the bars *C*. Since the bars *H* are adjustable, however, this furnishes means for adjusting the frames and their bars *E* after 110 said frames are put into the machine, so that the distance between the bars *C* and *E* is uniform throughout the entire width of the

apron. A bridge-plate K is pivoted to the girder B, and it extends over and rests upon the flange a^2 , and thus it prevents coal dumped from the car from falling down between 5 the apron and the girder and compels all of said coal to flow on to the screen, which has been described. Below these screens is the floor A⁶, onto which the material which passes the screen-bars will fall, and this screened 10 material sliding down said floor will flow into the tube M of the screen conveyer, which is constructed substantially as shown in my prior application, and it is associated with co-operating parts, as shown in said application.

15 Having described my invention, I claim—

1. In a car-dumping machine, the combination of an inclined apron which includes in its construction a plurality of parallel longitudinal beams, floor-plates secured upon the 20 lower parts of said beams, and a plurality of parallel longitudinal bars secured between the upper parts of said longitudinal beams at substantially the level of said floor-plates, with a plurality of frames located severally 25 between said longitudinal beams and below said bars, a plurality of longitudinal bars secured to each of said frames, and means for supporting said frames and adjusting them toward and from said upper bars.

30 2. In a car-dumping machine, the combination of an inclined apron which includes in its construction a plurality of parallel longitudinal beams, floor-plates secured upon the lower parts of said beams, and a plurality of 35 parallel longitudinal bars secured between the upper parts of said longitudinal beams at substantially the level of said floor-plates, with a plurality of frames located severally 40 between said longitudinal beams and below said bars, a plurality of longitudinal bars secured to each of said frames, shafts extending transversely of the apron and mounted in bearings supported by said longitudinal beams, and means carried by said shafts for 45 adjustably supporting said frames.

3. The combination with the vertically-movable apron-supporting girder of a car-dumping machine, an apron hinged thereto and capable of being held at various inclinations, which apron has a floor over its lower 50 part, and an upwardly-extended transverse flange near its upper end, a plurality of longitudinal bars whose rear upper ends pass through holes in said flange and whose front lower ends are fixed upon the floor of the 55 apron, a bridge-plate pivoted at its upper end to said girder and having its lower end supported on the apron and extended over the upper ends of said bars, and a plurality of longitudinal bars located below the spaces 60 between the bars first named.

4. In a car-dumping machine, the combination of an inclined apron, whose floor at the upper part of said apron is composed of a plurality of parallel longitudinal bars, a plurality 65 of frames located beneath said bars, and having each a plurality of longitudinal bars secured to it, shafts extending transversely of the apron, and a plurality of cams secured thereto engaging said frames, and 70 links connecting the upper end of said frame with the apron.

5. In a car-dumping machine, the combination of an inclined apron, whose floor at the upper part of said apron is composed of 75 a plurality of parallel longitudinal bars, a plurality of frames located beneath said bars, and having each a plurality of longitudinal bars secured to it, bars adjustably secured to 80 said frames, shafts extending transversely of the apron, and cams secured to said shafts engaging with said adjustable bars, and means for simultaneously rotating the shafts.

In testimony whereof I hereunto affix my signature in the presence of two witnesses.

JOHN McMYLER.
